[57] CLAIM

The ornamental design for a cart for refuse containers, as shown and described.

DESCRIPTION

FIG. 1 is a front perspective view of cart for refuse containers showing my new design;

FIG. 2 is a front elevational view thereof;

FIG. 3 is a side elevational view thereof, the opposite side elevational view being a mirror image of that shown;

FIG. 4 is a top plan view thereof;

FIG. 5 is a rear elevational view thereof;

FIG. 6 is a bottom plan view thereof.

FIG 1
